UNITED STATES PATENT OFFICE.

GEORGE C. FATSCHER AND CLARENCE E. BILLINGS, OF NEW HAVEN, CONNECTICUT,
ASSIGNORS TO THE NEW HAVEN SAND-BLAST COMPANY, OF NEW HAVEN, CONNECTICUT, A CORPORATION OF CONNECTICUT.

SAND-BLAST MACHINE.

Application filed March 26, 1923. Serial No. 627,680.

Our invention relates to sand blast machines, and particularly to apparatus of the rotary drum type.

Among the objects of our invention may be mentioned—

- (1) The automatic recovery of the blast sand for re-use;
- (2) The cleansing of the sand by a counter draft to remove dust and like particles therefrom so that the sand is kept in the best condition for its effective operation;
- (3) A more efficient blast mechanism;
- (4) A simple and rugged construction of the barrel elements—including ready accessibility for repair;
- (5) An improved drive for the barrel;
- (6) Various features of detail construction hereinafter pointed out or illustrated in the accompanying drawing in which—

20 Fig. 1 is a broken elevation of the charging end of an apparatus in which our invention is embodied in one form;

Fig. 2 is a vertical section on the line 2—2, Fig. 1;

25 Fig. 3 is a broken elevation of the elevator end of the machine;

Fig. 4 is a broken plan of the elevator drum; and

30 Fig. 5 is a section on the line 5—5, Fig. 2. The present apparatus is of the self-contained type and in certain particulars is related to its prototypes in the Dreisbach Patent No. 948,271, February 1, 1910, and the co-pending application of C. E. Billings Serial No. 627,693, and our copending application Serial No. 627,679, (now Patent No. 1,661,934) both filed herewith.

35 While the invention is capable of embodiment in various constructions, we have illustrated an apparatus which is simple and efficient. It comprises a rugged sheet metal barrel body 6, perforated at 7 to form a cylindrical screen for the reception of the castings or other articles to be sanded. The screen is clamped between the webs 8 and 9 of the bearing rings 10 and 11 by means of the tie bolts 12. The draw-up nuts 13 of the latter are exposed at the charging end of the barrel and are thus readily accessible for removal.

40 At one end the barrel is closed by a head 14 centrally apertured at 15 to admit a blast nozzle 16, and secured to the web 9 of the bearing ring 11 by bolts or rivets 17. At its

55 opposite end the barrel is closed by a semi-circular head 18 to which is hinged at 19 a complementary semi-circular door 20. The head 18 is integral with an annular flange 21 which is detachably fastened by cap screws 22 to the web 8 of the bearing ring 10. 60 Latches 23 carried by the door and engaging keepers 24, secured to the web 8 of the bearing ring 10, hold the door 20 normally closed.

65 The door 20 and head 18, as well as the head 14, are all protected against wear by renewable lining plates 25 spaced from their inner faces by bosses tapped to receive securing screws 26. In order to thoroughly ventilate the blast chamber, the door 20, head 14, and also the head 18, if desired, are perforated by holes 27, the draft escaping around the margin of the plates 25.

70 Surrounding the body 6 of the drum, but spaced therefrom, is a lighter sheet metal shell 28 which encloses the tie bolts 12 and 75 forms an annular chamber 29 for the reception of the sand which passes through the perforations of the screen body 6 after sifting through the charge of castings. Within the annular chamber and secured to the shell 80 28, is arranged a spiral rib 30 extending from end to end of the barrel and serving as means for causing the automatic return of the sand to the elevator end of the barrel.

75 The web 9 of the bearing ring 11 is apertured at appropriate points 31 to permit the escape of the sand delivered by the spiral 30 to the elevator drum 32. The latter is of relatively light sheet metal construction and is secured by cap screws to the outer face of 90 the web 9 of the bearing ring 11, so that it rotates therewith. The drum is divided into a pair of longitudinally adjacent channels 33 and 34 by a ring partition 35, held in position by series of brackets 36 and 37 forming 95 elevator buckets for lifting the sand delivered to the drum from the barrel body. Within the upper portion of the drum is arranged a chute 38 into which the sand is discharged by the buckets 36 of the channel 100 33, which receives the sand directly from the drum through the ports 31. A guard plate 39 at the top of the chute extends toward and lies adjacent the ring partition 35, to prevent the escape of the sand into the channel 105 34 on its discharge from the buckets 36. At its lower end the chute 38 is offset and its discharge port 40 is arranged to deliver to

the channel 34 of the drum. Deflecting aprons or baffles 41 may be arranged within the chute to scatter the sand and cause it to travel a tortuous course therethrough, and thus to permit the counter blast to permeate the sand and carry off entrained dust particles.

A second chute 42 adjacent the top of the drum is arranged to receive the sand delivered by the buckets 37 of the channel 34 and to deliver the same to the hopper of an independent external pressure tank 43 diagrammatically shown in Fig. 2.

The elevator drum 32 is closed at its outer end by a stationary tri-part head 44 supported by a frame 45. The chute 38 is secured to the frame 45, while the chute 42 is mounted in the upper portion of the central section of the head 44. Brackets on the side section 44^a of the head are bolted to the uprights of the frame 45 to permit of the ready removal of this section of the head for access to the interior of the elevator drum. Supported upon the interior of the head 44 is a section box 46 communicating with the interior of the chute 38 and opening to the suction pipe 47 which leads to a fan (not shown) for creating a draft through the apparatus. It will be noted that the air entering the suction box from the lower end of the chute 38 passes upward through the down legs 51 and 52 of the chute 38 and counter to the fall of sand therethrough.

The sand delivered to the hopper of the pressure tank 43 is fed in well known manner to the mixing box, to which air under pressure enters through the pipe 48, and from which the sand under pressure is carried through flexible tubes 49 and 50 to the blast nozzles. The tube 49 passes through an aperture in the head 44, and between the down legs 51 and 52 of the chute 38, and is connected in any suitable way to the nozzle 16 which is adjustably supported at 53 on the bracket 54. The second tube 50, leading from the pressure chamber of the hopper 43, is connected to the second blast nozzle 55 arranged at the opposite end of the barrel and delivering into the blast chamber through a central aperture 56 formed partially in the closure head 18 and partially in the door 20. The nozzle is adjustably supported at 57 on a bracket 58, which in turn is vertically adjustable on the rod 59 pivoted in its support 60. The bracket 58 is held in adjusted position on rod 59 by the set screw 61, while a clamping screw 62, or any other suitable device, is provided for holding the rod 59 against rotation under the influence of the reaction exerted on the nozzle when the blast is in operation. Both nozzles 55 and 16 carry guards *g* of a construction such as indicated in our copending application filed herewith. It will be understood that when the nozzles are adjusted to different positions, it is necessary to substi-

tute different guards which properly accommodate the nozzle, while at the same time fitting the opening in the drum head.

The bearing rings 10 and 11 rest on pairs 63 and 64 of supporting wheels keyed to shafts 65 and 66 on which are secured worm wheels 67 and 68 meshing with worms 69 and 70 on the shaft 71. The latter is arranged centrally beneath the barrel and carries fast and loose pulleys 72 and 73 for a driving belt. The frame 74 supports the driving shaft 71 and extends between the pedestals 75 upon which the roller shafts 65 and 66 are journaled. Housings 76 completely enclose the worm gears and maintain the latter free from dust, while the bearing boxes for the worms are so shaped as to form closed oil or grease pockets 77, thus permitting the gears to run submerged in lubricant free from dust.

The operation of the apparatus is readily understood. Assuming the machine to be empty and at rest, and the parts in the position shown in Fig. 1, the bracket 58 carrying the nozzle 55 is swung out of obstructing position, the door latches 23 released, and the door 20 swung down to open position. The castings are then charged into the barrel and when a sufficient load has been introduced, the door 20 is swung up and the latches 23 fastened. The nozzle bracket 58 is then returned to position and the clamping screw 62 fastened to hold the nozzle in position during operation. The driving belt is shifted to the fast pulley 72, thus setting the rollers 63 and 64 in motion and imparting rotation to the barrel and elevator drum. The suction fan is set in motion to exhaust the barrel through the suction box 46 and pipe 47. The blast control devices are then operated to deliver sand from the pressure tank to the nozzles 16 and 55. As the spent sand filters from the blast chamber through the screen 7 it is conveyed by the spiral rib 30 toward the elevator drum, and falling through the openings 31 is caught by the buckets 36 and lifted to the upper portion of the drum, where it falls into the chute 38. Passing down through the latter counter to the suction draft, it is freed of entrained dust and delivered clean to the buckets 37 of the elevator drum. These buckets again lift the sand and discharge it to the chute 42, from which it passes to the hopper 43 of the blast device, which again returns it through the hose connections 49 and 50 to the nozzles 16 and 55. When the castings have been sufficiently cleaned the barrel is stopped, preferably with the door in "up" position, illustrated in Fig. 1. The bracket 58 carrying nozzle 55 is swung out of obstructing position, the door latches 23 are freed and the door swung down, where it is temporarily engaged and held open by the latch 78. The barrel is then again rotated and the castings fall out as the door opening moves downward. If desired,

the drum may be halted when the door opening is down and the castings be then raked out —or rotation may be continued until the castings work out automatically.

5. Various modifications in details of construction will readily occur to those dealing with the problem without departing from what we claim as our invention.

We claim—

- 10 1. In sand blast apparatus, the combination with an exterior pressure sand blast tank, of a rotary sand blast barrel formed from perforated heavy sheet metal, a surrounding lighter sheet metal shell spaced therefrom, deflecting means arranged in the space between the barrel and shell for deflecting to one end of the barrel the sand passing through the perforations of the barrel body, a lifting drum of light sheet metal 15 rotating with the barrel body and adapted to receive and elevate the sand deflected to said end of the body, means for delivering the lifted sand to the exterior sand blast tank, a rotary head at the opposite end of the barrel, 20 said head including a charging and discharging door, together with a nozzle adapted to discharge through said rotary barrel head the sand blast derived from the pressure tank.
- 20 2. In sand blast apparatus, the combination with an exterior pressure sand blast tank, of a rotary sand blast barrel, means for playing sand under pressure from said sand blast tank upon a charge within the barrel, 25 a rotary lifting drum at one end of the barrel, means for diverting to said drum the sand discharged into the barrel, means for causing a draft to pass through said drum, said drum discharging through said draft 30 the sand received from the barrel to remove entrained dust therefrom and serving to lift the cleaned sand apart from the sand received directly from the barrel, together with means for diverting the lifted and cleaned sand to the pressure tank.
- 30 3. In sand blast apparatus, a rotary blast barrel having at one end a centrally apertured rotary end closure movable to permit charging and discharging of the barrel, and 35 means for supporting a nozzle at the aperture, said support being movable to shift said nozzle away from the aperture.
- 40 4. In sand blast apparatus, a rotary blast barrel apertured at one end and having a swinging door at said end, means for supporting a nozzle at the aperture, said support being movable independently of the door to shift said nozzle out of door-obstructing position.
- 45 5. A rotary sand blast barrel having at one end a hinged closure rotating therewith but affording a charging and discharging opening, said barrel end being centrally apertured to permit the play of a sand blast there- 50 through on a charge within the barrel, an in-

dependently pivoted hinge rod vertically arranged adjacent said apertured barrel end, a bracket vertically adjustable on said hinge rod, and means associated with the bracket for supporting a blast nozzle at the central 70 aperture in the barrel end.

6. A sand blast barrel having at one end an elevator drum comprising a plurality of series of elevator buckets spaced longitudinally of the drum axis, partitioning which separates each bucket series from the adjacent bucket series, chute means within the drum for receiving the discharge from one bucket series and delivering it to another bucket series, and a suction wind box opening to the upper portion of the chute for creating a draft therethrough counter to the fall of the sand.

7. A rotary sand blast barrel having at one end a stationary chute for sand delivered thereto from the barrel, a suction wind box opening to the chute for creating a draft therethrough, means for elevating blast sand from the barrel and discharging the same through the chute counter to the draft, and 90 means for delivering the sand passing through the chute to an exterior pressure blast device.

8. A rotary sand blast barrel having at one end a stationary chute for sand delivered thereto from the barrel, a suction wind box opening to the chute for creating a draft therethrough, means for elevating blast sand from the barrel and discharging the same through the chute counter to the draft, and 100 means for delivering the sand passing through the chute to an exterior hopper, together with baffles arranged in the chute for dispersing the sand across the draft.

9. A rotary sand blast barrel having at one end a rotary elevator drum; a stationary closure head for one end of the drum an external pressure blast tank having a collecting hopper, a chute passing through said closure head for delivery to the sand-collecting hopper of an external pressure tank, and means carried by said drum for lifting and discharging to said hopper spent sand led to said drum from the barrel in combination with blast nozzles adapted to play through the opposite ends of the barrel upon a charge within the latter, and connections from said nozzles to the pressure tank.

10. A rotary sand blast barrel having at one end a rotary elevator drum, a stationary closure head for one end of the drum, a chute passing through said closure head for delivery to an external hopper, and means carried by said drum for lifting and discharging to said hopper spent sand led to said drum from the barrel, together with means within the drum for removing entrained dust from the sand in advance of its delivery to the chute.

11. A sand blast apparatus comprising a

rotary drum having at one end a charging door opening, together with a door rotating with the barrel and apertured to admit a blast nozzle to play upon a charge within the barrel.

12. A sand blast apparatus comprising a rotary drum having at one end a charging door opening, together with a door rotating with the barrel and apertured to admit a blast nozzle to play upon a charge within the barrel, together with means for supporting the nozzle at said blast aperture.

13. A sand blast apparatus comprising a rotary drum having at one end a charging door opening, together with a door rotating with the barrel and apertured to admit a blast nozzle to play upon a charge within the barrel, together with means for supporting the nozzle at said blast aperture, and a guard for closing the blast aperture around the nozzle.

14. A sand blast apparatus comprising a rotary barrel having at one end a charging and discharging opening, a rotary closure for said opening, said closure being apertured, and means for playing the sand blast through the aperture in said rotary end closure upon a charge within the drum.

15. A sand blast apparatus comprising a rotary shell, a rotary screen arranged within and spaced from the shell, bearing rings at opposite ends of the barrel, and clamping bolts extending between said bearing rings

in the area between said shell and screen and serving to clamp the parts together, in combination with rotary end closures for the barrel detachably secured respectively to the end faces of the bearing rings to permit the removal of said end closures without disturbance of the body structure of the barrel one of said end closures including a hinged charging door, and the other of said end closures carrying a rotary lifting drum for the recovery of sand diverted thereto from the drum.

16. A sand blast apparatus comprising a rotary barrel, bearing rings at the opposite ends of the barrel, rotatable end closures for the barrel secured to said bearing rings, and blast nozzles playing through central openings in the end closures upon a charge within the barrel, in combination with an elevator drum secured to the bearing ring at one end of said barrel.

17. In a sand blast barrel having at one end a rotary elevator drum, a stationary sectional closure head for the outer end of the drum, one section of the closure head being readily removable to permit access to the interior of the drum together with a chute secured to said section and normally supported thereby within the elevator drum.

In testimony whereof we have signed our names to this specification.

GEORGE C. FATSCHER.
CLARENCE E. BILLINGS.
